Primary Examiner — Darcey E Gottschalk*(74) Attorney, Agent, or Firm* — Harness, Dickey & Pierce, P.L.C.(57) **CLAIM**

The ornamental design for a combination clamshell-outer box, as shown and described.

DESCRIPTION

FIG. 1 is a perspective view of a combination clamshell-outer box;

FIG. 2 is a front elevation view of the combination clamshell-outer box of FIG. 1;

FIG. 3 is a rear elevation view of the combination clamshell-outer box of FIG. 1;

FIG. 4 is a left elevation view of the combination clamshell-outer box of FIG. 1;

FIG. 5 is a right elevation view of the combination clamshell-outer box of FIG. 1;

FIG. 6 is a top plan view of the combination clamshell-outer box of FIG. 1; and,

FIG. 7 is a bottom plan view of the combination clamshell-outer box of FIG. 1.

In the drawings, the broken lines showing portions of the combination clamshell-outer box depicts environment, and forms no part of the claim.
